UNITED STATES PATENT OFFICE.

JOHN TINGLEY, OF WATERFORD, NEW JERSEY.

IMPROVEMENT IN CHURNS.

Specification forming part of Letters Patent No. 39,507, dated August 11, 1863.

To all whom it may concern:

Be it known that I, JOHN TINGLEY, of Waterford, in the county of Camden and State of New Jersey, have invented a new and useful Improvement in Churns; and I do hereby declare the following to be a true and exact description thereof, reference being had to the accompanying drawings, making a part of this specification, in which—

Figure 1 is a perspective view of a churn constructed with my improvement. Fig. 2 is an end view of the same. Fig. 3 is an edge view of the "head." Fig. 4 is a vertical section of a portion of the head. Fig. 5 is an edge view of one of the staves of the churn. Fig. 6 is a plan view of the clamp, all of which will be described more fully hereinafter.

My invention consists in providing the ordinary barrel-churn with a head, which may be removed at pleasure for the purposes of filling, emptying, cleaning, and airing.

To enable others to make and use my invention, I will proceed to describe its construction and operation.

I construct my churn in the ordinary manner of constructing barrel-churns, with the exceptions of the movable head and the clamping-hoop, as hereinafter described.

Fig. 1 represents a churn with my improvement in perspective, A being the body of the same; B, the movable head; C, the upper and clamping-hoop, and D the axle of the dashers. The head B, I construct with a slightly-beveled edge, grooved as shown in Fig. 3, E being the groove. This groove I fill with a strip of some suitable elastic substance—as india-rubber—projecting beyond the edge, as shown in Fig. 4, in which F is a section of the elastic strip. The upper ends of the staves of the churn are beveled on the inner side, as shown at G, Fig. 5. Thus when the head is put in place, as the bevel on the edge of the head and the bevel on the inner side of the upper end of the staves correspond, an almost perfect joint would at once be formed, and this joint, by means of the projecting elastic band F and the clamping-hoop C, would be rendered perfectly water-tight and secure. The clamping-hoop C rests in the rabbet H, turned on the outside of the upper end of the barrel.

The clamp is constructed and operated as follows: A metallic plate, I, Figs. 1, 2, and 6, of about the same width of the hoop and made to fit the curvature of the rabbet H, is provided with a projecting lug, K. To one end of this plate an end of the hoop is securely fastened, as seen at L. A curved bifurcated lever, M, is pivoted to the lug K. This lever is provided with a link, N, or other equivalent device, which passes through or is pivoted to the lever a short distance from the pivot through the lug. The other end of this link is attached to the free end of the hoop. It will now be seen that when the lever is thrown back, as indicated by the red lines of Fig. 2, the free end of the hoop will be thrown back also, and the hoop loosened, so that, the pressure upon the edge of the head being removed, it can be easily withdrawn and the churn emptied or cleaned without trouble.

When the churn is to be used, it is only necessary to place the head in proper position and to throw the lever into the position indicated in Figs. 1, 2, and 6, when the ends of the hoop will be drawn toward each other, constricting the upper ends of the staves and rendering the joint between the staves and the head perfectly tight. The line of draft of the link being carried inside the center upon which the lever moves, (as at Fig. 2,) it must remain in that position until force is applied to the lever to draw it back toward the position indicated by the red lines.

In use the churn may be laid upon its side in the ordinary position of barrel-churns.

What I claim as my invention, and desire to secure by Letters Patent, is—

1. The clamping-hoop C, operated by the lever M, link N, and plate I, or their equivalents, substantially as described.
2. The head B, provided with the groove E and the elastic strip F, or their equivalents, in combination with the clamping-hoop, the lever, the link, and the plate, as above described.

JOHN TINGLEY.
